FIG. 4.

S. W. METZ, INVENTOR
by *Victor J. Evans*
ATTORNEY

UNITED STATES PATENT OFFICE.

SILAS W. METZ, OF CONNELLSVILLE, PENNSYLVANIA.

TOOTHBRUSH.

Application filed April 4, 1923. Serial No. 629,866.

To all whom it may concern:

Be it known that I, SILAS W. METZ, a citizen of the United States, residing at Connellsville, in the county of Fayette and State of Pennsylvania, have invented new and useful Improvements in Toothbrushes, of which the following is a specification.

This invention relates to tooth brushes.

One of the main objects of the invention is to provide a tooth brush of simple and efficient construction by means of which the teeth may be quickly and thoroughly brushed and cleansed, the brush being so constructed as to effectually clean between the teeth. A further object is to provide a tooth brush so constructed as to enable the user to thoroughly clean between the three rearmost teeth on the upper and lower jaws. Further objects will appear from the detailed description.

In the drawings:—

Figure 1 is an underneath view of the brush;

Figure 2 is a side view;

Figure 3 is a front view showing the manner of using the brush for cleaning the outer surfaces of the teeth;

Figure 4 is a plan view showing the manner of using the brush for cleaning the lower teeth.

I construct the brush with a handle 1 from which extends a head 2 which is of substantially U-shape in outline. This head includes an arcuate bridge 3 which extends an equal distance to each side of handle 1, this bridge being positioned substantially in the plane of the handle. An arm 4 projects from each end of bridge 3. These arms converge toward each other, and each arm is curved upwardly, as clearly illustrated in Figure 2. The curvature of the arms 4 is intended to conform to the normal curvature of the user's jaw, and the slant or angle of these arms relative to

bridge 3 is intended to conform to the slant or angle of the jaws when the mouth is open for brushing the teeth. Each arm 4 is provided with depending bristles 5, these bristles extending about bridge 3, from each end thereof, to within a short distance of handle 1. With the brush in the position illustrated in Fig. 3, the outer surfaces of the teeth of the upper and lower jaws may be readily cleaned simultaneously and, by imparting a vertical reciprocating motion to the brush the bristles 5 serve to effectu-

ally clean between the teeth. By holding the brush with head 2 thereof in horizontal position the upper surfaces of the teeth of the upper or lower jaws may be quickly and thoroughly cleaned. Attention is called to the fact that when the head 2 of the brush is in vertical position, the curved arms 4 conform to the curvature of the jaw thus insuring thorough brushing and cleaning between the teeth as well as on the outer surfaces thereof. By holding the brush in horizontal position so that handle 1 is in contact with the cheek, the inner arm 4 is so positioned as to contact with the inner or rearmost teeth at that side of the jaw so that by reciprocating the brush across the teeth bristles 5 will act to thoroughly brush the upper surfaces of the teeth and also to effectually brush between the teeth so as to thoroughly clean the same and remove all particles of food or other foreign materials. It is a known fact that the rearmost or inner teeth or molars decay more rapidly than the other teeth and this is due primarily to the fact that these are the chewing teeth and that particles of food become pressed or packed between these teeth, which particles are not entirely removed by using the ordinary type of tooth brush due to the fact that, with a tooth brush having the head in alignment with the handle, it is impossible to brush transversely of the inner or rear molars so as to effectually brush and clean between these teeth. My brush provides simple and efficient means for readily accomplishing this very desirable result and, in this respect, is a decided improvement over the ordinary type of tooth brush. Also, as above pointed out, my brush provides very simple and efficient means whereby the teeth may be thoroughly cleansed and brushed much more quickly than with the ordinary type of tooth brush.

What I claim is:—

1. In a tooth brush of the character described, a substantially U-shaped head having its arms of arcuate shape and converging away from the bight portion of the head, the bight portion of the head also being of arcuate shape, and a handle extending from the central part of the bight portion of said head, the arms being provided with depending bristles.

2. In a tooth brush of the character described, a substantially U-shaped head having its arms of arcuate shape and converging

ing away from the bight portion of the head, the bight portion of the head also being of arcuate shape, and a handle extending from the central part of the bight portion of said head, the arms being provided with depending bristles terminating a short distance beyond the angles of the arms with the bight portion of the head.

3. In a tooth brush of the character described, a handle provided at one end with

an integral head of substantially U-shape, said head having its arms of arcuate shape and converging away from the bight portion of the head, said handle being disposed substantially in the plane of the head and 15 the arms being provided with downwardly directed bristles.

In testimony whereof I affix my signature.

SILAS W. METZ.
